WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

HARP-STOP FOR PIPE-ORGANS.

1,173,507.

Specification of Letters Patent. Patented Feb. 29, 1916.

Application filed April 29, 1912. Serial No. 693,785.

To all whom it may concern:

Be it known that I, WILLIAM E. HASKELL, of Brattleboro, in the county of Windham and State of Vermont, have invented a 5 Harp-Stop for Pipe-Organs, of which the following is a specification.

The object of the present invention is to provide a pipe organ with a stop which shall give a tone similar to that of a man- 10 ually played harp.

In accordance with the present invention, each note of the harp stop comprises a glass bar which is struck by a pneumatically actuated hammer; a resonator associated with 15 the glass bar; a corroborating open labial pipe; and key-controlled instrumentalities for concurrently actuating said hammers and causing the corroborating pipes to speak.

20 The new stop is illustrated in accompanying drawings, wherein—

Figure 1, is a vertical -cross section through one of the vibrating glass bars, the associated resonator, pipe and hammer, and 25 the pneumatic appliances for moving the hammer and for sounding the pipe. The section is taken on the plane indicated by the line 1—1, in Fig. 3. In Fig. 1, the hammer is shown in its idle position of rest. Fig. 2, is a view similar to Fig. 1, excepting that certain of the parts are shown in elevation instead of in section, and the hammer is shown in the position which it occupies just after it has struck the vibrating glass 30 bar. Fig. 3, is a horizontal view, partly in section in the plane indicated by the line 3—3 in Fig. 1. Figs. 4 and 5, are face views of vibrating glass bars. Fig. 6, is a chart illustrating the arrangement of the 35 various sounding devices of the stop as the same are assembled in the organ. Fig. 7 is a detailed view of one of the resonators and glass bars. Fig. 8, is a chart illustrating the 40 dimensions of the glass bars and their resonators for the different notes in the stop. Figs. 9 and 10, are enlarged detail sections of the retaining means for one of the 45 vibrating glass bars, taken respectively at the places indicated at 9—9 and at 50 10—10 in Fig. 3.

In accordance with the present invention, as illustrated in the drawings, each note of the harp stop of the organ comprises a vertically hanging vibrating glass sound-

ing bar A, a horizontal resonator B, a vertical swinging hammer C, and a vertical open labial pipe D.

The hammer C, is pivoted at its lower end at a, and it normally occupies the idle position shown in Fig. 1, resting against a padded stop rail b, which extends longitudinally and horizontally and is common to all hammers for the same rank of glass sounding bars. The hammer is immediately acted upon by a striking pneumatic E, 65 which, when supplied with compressed air, expands, as shown in Fig. 2, thereby swinging the hammer and striking the glass bar A, and setting it into vibration. When compressed air is cut off from the striking 70 pneumatic, the hammer is restored to its position of rest by a spring c.

The striking pneumatic E, is expanded when the corresponding key of the organ is played by the instrumentalities illustrated. 75 When the draw stop or stop key (as the case may be) is manipulated, which governs the harp stop, air under pressure is admitted into the stop chamber F. Communication between the stop chamber and a series of 80 passages d, is controlled by double valves G, of familiar construction, there being one of the double valves G, and one of the passages d, for each of the glass bars. Each double valve G, is immediately governed by a solenoid H. Normally, each double valve G, occupies the position shown in Fig. 1, and accordingly, when the stop key or draw stop is manipulated, the air under pressure admitted into the chamber F, goes through 85 each passage d, and into the interior of a primary pneumatic I, maintaining it in expanded condition. The construction of the illustrated pneumatic is that shown in Letters Patent of the United States, No. 95 923,263, June 1, 1909. This primary pneumatic I, is connected with a double valve J, controlling the admission of air from a wind-chest K, containing air under pressure to a passage e, leading to the interior of a 100 secondary pneumatic L, located within the wind-chest K.

When the primary pneumatic I, occupies its expanded position, shown in Fig. 1, the double valve J, is held uplifted so that 105 the interior and the exterior of the secondary pneumatic L, are subjected to equal pressure, and the movable lower wall of the

secondary pneumatic is maintained in its lowermost position, shown in Fig. 1, by gravity. A double valve M, is connected with the secondary pneumatic L, and it normally occupies the position shown in Fig. 1, venting to the open air a passage f, leading to the interior of the striking pneumatic E, and through a branch passage g, to the corroborating labial pipe D. When, however, the corresponding key of the organ is played, an electric circuit is closed, thereby energizing the solenoid H, and lifting the double valve G, to the position shown in Fig. 2. This closes communication from the stop chamber F, to the passage d, and vents said passage to the open air and, accordingly, the primary pneumatic I, collapses by gravity, thus lowering the double valve J. This cuts off the supply of air from the wind-chest K, to the passage e, and vents said passage to the open air. Accordingly, the secondary pneumatic L, is collapsed by the greater external air pressure within the wind-chest K, thus lifting the double valve M, and opening the single port which admits wind to effect the sounding of a glass bar and the speaking of its corroborating pipe. This lifting of the double valve M admits air under pressure from the wind-chest into the wind passage f, and closes the vent therefrom to the open air. Part of the air thus admitted to the wind-passage f, enters and expands the striking pneumatic C, and part of it passes through the passage g, to the corroborating pipe D. Accordingly, the hammer C, strikes the glass bar A, putting it in vibration, and the corroborating pipe D, speaks until the finger of the organist is removed from the corresponding key of the keyboard. When the finger is removed from the corresponding key, all of the instrumentalities resume the normal idle position of rest shown in Fig. 1.

By reason of the loose connection N, between the striking pneumatic E, and the hammer C, illustrated in Fig. 1, and the adjustable padded limiting stop h, which limits the outward expansion of the striking pneumatic, the hammer strikes the glass sounding bar by its momentum, as indicated by dotted lines in Fig. 2, and is instantaneously moved by the spring e, (and by its rebound), to the position shown in full lines in Fig. 2, so that it does not muffle the vibrations of the glass sounding bar. The hammer has an inserted cushioned, thick soft felt striking pad i, and it is weighted by a transverse lead plug j, at its head, so as to increase its striking momentum.

The details of the vibrating glass sounding bars and of their resonators are of great importance in the production of the desired quality of tone. A harp string, when plucked by the finger of a skilled harpist, emits a pronounced sound, followed by a characteristic

vibration. Extended experiments show that the quality of the harp tone can be secured by a properly selected and mounted bar of glass when reinforced by a properly proportioned and located resonator and by a soft, corroborating labial pipe which will give a sustained tone as long as the corresponding key of the organ is held. 70

Each glass bar A, is suspended in front of its own resonator and hangs vertically. At the top of the resonator is a bracket k, carrying a horizontal rail O, (Fig. 10), having a centrally located, outwardly projecting screw threaded metal pin l, which passes through a hole m, in the glass bar midway between its side edges. The bar A, is held in position by means of a collar n, screwing on to the pin l. The vibrations of the glass bar are prevented from being transmitted to the metal pin by means of a felt sleeve o, surrounding the pin within the hole of the glass bar, by a felt washer p, upon the pin between the outer face of the glass bar and the collar n, and by a felt-strip q, between the inner face of the glass bar and the rail O. The lower portion of the glass bar is held in place between a felt strip r, (see Fig. 3), at the front face of a horizontal rail P, secured to a bracket k, on the under side of the resonator and a second felt strip s, in front of the glass bar, which is carried by a rail Q, which is slidingly and yieldingly mounted upon two rods t, and is maintained in its outer position by springs u. Accordingly, the lower portion of the glass bar is loosely held, leaving it free to vibrate but at the same time it cannot make bearing against a rigid material either front or back. 95

The glass bar is suspended at a nodal point. The hammer strikes it at its middle and the suspending aperture m, is one-fourth of the length of the glass bar below its top. The retaining felted rails P, and Q, are located one-fourth of the way up from the lower edge of the glass bar. Each glass bar is provided with a second nodal hole w, (see Figs. 4 and 5), symmetrically located with respect to the hole m. The glass bars are made in the first instance of appropriate dimensions, but owing to the lack of homogeneity in the glass and the difficulty of getting it of exact uniform thickness, tuning is sometimes necessary. By cutting away at the opposite sides as indicated at x, x, in Fig. 4, the pitch is flattened, and by filing away at the top or bottom (preferably both to obtain symmetry) the pitch is sharpened. It is important to use the best quality of plate glass. 115

Each resonator is of wood and it is rectangular in cross section. The vertical dimension or depth of the resonator is greater than its width, except in the upper octave, and the horizontal dimension or length is greater than either width or depth, as is 130

seen by comparing Figs. 2 and 3. The resonator is open at its end toward the glass bar. It is closed at the other end by an adjustable tuning stopper S, similar to the tuning 5 stoppers used in stopped labial pipes. The interior width of each resonator is slightly greater than that of the glass bar associated therewith, and the front edges of the four walls of the resonator are beveled externally 10 to a sharp edge as indicated at y, in Figs. 1 and 3. It is important in order to get the proper effect that this beveled edge should be presented.

The rectangular resonator has thick, 15 strong, flat wooden walls. The mouth of the resonator is wider than the glass bar to facilitate the escape of the sound waves. These thick walls are beveled at their edges at the mouth of the resonator. The size of 20 each resonator lengthwise is of approximately the entire length of the corresponding glass bar.

Each of the corroborating pipes D, is an 25 open pipe of the proper speaking length to have the same pitch as the corresponding glass bar.

The harp stop as it has been made, includes four full octaves, that is to say, forty-nine notes extending from C, to c⁴. Accordingly, the pipe of lowest note is of four-foot 30 speaking length. The lowest pipe is therefore of the proper length to give a four-foot tone and it is two and one-half inches wide and three inches deep, (inside measurements), the "depth" being the dimension 35 between the front wall, in which the mouth is formed, and the rear wall. The other pipes follow the recognized diminishing proportions for the remaining notes of the 40 stop in accordance with well understood acoustic principles of pipe organ construction. The drawings illustrate the pipe D, conventionally only, and do not show its full length, or its proper proportions with 45 respect to the illustrated resonator, since the dimensions of such pipes for different pitches are well known.

Each glass bar should be one-fourth of 50 an inch thick. Inevitable variations are compensated for by tuning. Fig. 8, illustrates diagrammatically and by scale the proper length and width of all the glass bars of the stop, and the interior dimensions 55 of the corresponding resonators. This chart indicates that in every instance the width of the resonator is greater than that of the corresponding glass bar. In each case, the glass bar should be symmetrically located widthwise of the mouth of the corresponding 60 resonator.

Each glass bar is located forward of the front edge of the corresponding resonator, as shown in Figs. 1 and 2, so that there is 65 a free space between them. This varies from about three-eighths of an inch at the lowest

note to slightly less than one-fourth of an inch for the upper note.

It has been found in practice that if the several glass bars and resonators are arranged in regular order in accordance with 70 the chromatic scale, the resonators nearest to that one whose glass bar is struck will respond, thus adversely modifying the desired tone. This is obviated by irregularly arranging the resonators and glass bars so 75 that no two differing by a semi-tone shall be next each other. Fig. 6, is a diagram illustrating an irregular disposition which has been demonstrated to be efficient. The sounding devices are arranged in four banks 80 located vertically one above the other, and the notes in each bank are disposed as indicated, so that neighboring notes are at least a full tone apart.

As indicated in Fig. 1, the wind pressure 85 in the chest K, should be relatively high so as to effectively impel the hammers C, while the pressure in the stop chamber F, may be relatively low since the wind there has but little mechanical work to perform. 90

I claim:

1. A harp stop for pipe organs comprising, in combination, vertically hanging glass sounding bars, each suspended at a nodal point; pneumatically actuated hammers, 95 each of which is located to strike the middle of one of the glass bars; a resonator rectangular in cross section for each glass bar, each resonator being horizontally disposed with its open mouth opposite its glass bar, with 100 an adjustable stopper at its opposite end, the mouth of the resonator being wider than the corresponding glass bar and spaced therefrom a distance at least equal to the thickness of said bar, and the four walls of the 105 resonator being externally beveled at its mouth; an open labial corroborating pipe for each glass bar; and key-controlled instrumentalities for concurrently actuating 110 said hammers and causing the corresponding

2. A harp stop for pipe organs comprising, in combination, vertically hanging glass sounding bars, each suspended at a nodal point; pneumatically actuated hammers, 115 each of which is located to strike the middle of one of the glass bars; a resonator rectangular in cross section for each glass bar, each resonator being horizontally disposed with its open mouth opposite its glass bar, with a 120 stopper at its opposite end, the mouth of the resonator being wider than the corresponding glass bar and spaced therefrom, and the four walls of the resonator being externally beveled at its mouth; a corroborating pipe 125 for each glass bar; and key-controlled instrumentalities for concurrently actuating said hammers and causing the corresponding corroborating pipes to speak.

3. A harp stop for pipe organs compris-

ing, in combination glass sounding bars; pneumatically actuated hammers, each of which is located to strike one of the glass bars; a resonator for each glass bar having its open mouth opposite its glass bar, the mouth of the resonator being wider than the corresponding glass bar and spaced therefrom; a corroborating pipe for each glass bar; and key-controlled instrumentalities for concurrently actuating said hammers and causing the corresponding corroborating pipes to speak.

4. A harp stop for pipe organs comprising, in combination, vertically hanging glass sounding bars, each suspended at a nodal point; pneumatically actuated hammers, each of which is located to strike the middle of one of the glass bars; and a resonator rectangular in cross section for each glass bar, each resonator being horizontally disposed with its open mouth opposite its glass bar, with an adjustable stopper at its opposite end, the mouth of the resonator being wider than the corresponding glass bar and spaced therefrom, and the four walls of the resonator being externally beveled at its mouth.

5. A harp stop for pipe organs comprising, in combination, vertically extending glass sounding bars; a hammer for each bar; and a resonator rectangular in cross section for each glass bar, each resonator being horizontally disposed with its open mouth opposite its glass bar, the mouth of the resonator being wider than the corresponding glass bar and spaced therefrom, and the four walls of the resonator being externally beveled at its mouth.

6. A harp stop for pipe organs comprising, in combination, glass sounding bars; a hammer for each bar; a resonator rectangular in cross section for each glass bar, each resonator having its open mouth opposite its glass bar, the mouth of the resonator being wider than the corresponding glass bar and spaced therefrom, and the four walls of the resonator being externally beveled at its mouth.

7. A harp stop for pipe organs comprising, in combination, glass sounding bars, a hammer for each bar; and an open mouthed resonator rectangular in cross section with its mouth opposite each bar, said mouth being wider than the width of the bar, and the dimension of said mouth lengthwise of the bar being greater than the width of said mouth.

8. A harp stop for pipe organs comprising, in combination, glass sounding bars; a pneumatically actuated hammer for each bar; an open mouthed resonator with its mouth opposite each bar; a corroborating pipe for each bar; and key-controlled instrumentalities for concurrently actuating said hammers and causing the corresponding corroborating pipes to speak.

9. A harp stop for pipe organs comprising, in combination, glass sounding bars; a hammer for each bar; a resonator opposite each bar; a corroborating pipe for each bar; and key-controlled instrumentalities for concurrently actuating said hammers and causing the corresponding corroborating pipes to speak.

10. A harp stop for pipe organs comprising, in combination, sound bars; a hammer for each bar; and an open mouthed wooden resonator with its mouth opposite each bar, each wall of the resonator being externally beveled at the mouth of the resonator where said wall is opposite the inner face of the sounding bar.

11. A harp stop for pipe organs having, in combination, a vertically hanging glass sounding bar having a hole at a nodal point near each end and midway between its sides; a suspending pin passing through the upper of said holes; a padded sleeve around said pin and within said upper hole; padded rails back of said bar at the top and bottom nodal holes; a padded collar surrounding said pin in front of said bar; and a yieldingly mounted movable padded rail in front of said bar at its lower nodal hole.

12. A harp stop for pipe organs having, in combination, a vertically hanging glass sounding bar having a hole at a nodal point near each end and midway between its sides; a suspending pin passing through the upper of said holes; a padded sleeve around said pin and within said upper hole; padded rails back of said bar at the top and bottom nodal holes; a padded collar surrounding said pin in front of said bar; and a padded rail in front of said bar at its lower nodal hole.

13. A harp stop for pipe organs having, in combination, a vertically hanging glass sounding bar having a hole at a nodal point near each end and midway between its sides; a suspending pin passing through the upper of said holes; a padded sleeve around said pin and within said upper hole; padded rails back of said bar at the top and bottom; a padded collar surrounding said pin in front of said bar; and a padded rail in front of said bar at its lower end.

14. A harp stop for pipe organs having, in combination, a vertically hanging glass sounding bar having a hole at a nodal point near its upper end and midway between its sides; a suspending pin passing through the upper of said holes; rails back of said bar at the top and bottom; a collar surrounding said pin in front of said bar; and a yieldingly mounted movable rail in front of said bar at its lower end.

15. A harp stop for pipe organs having, in combination, glass sounding bars; a pivoted hammer for each of said bars, said hammer being weighted by an inserted lead

plug at its head and having a thickly padded striking face; a padded stop rail against which said hammer rests; a striking pneumatic loosely connected with said hammer; 5 a padded stop limiting the impelling movement of said pneumatic; and a spring to return the hammer to its position of rest.

16. A harp stop for pipe organs having, in combination, glass sounding bars; a pivoted hammer for each of said bars, said hammer being weighted at its head having a thickly padded striking face; a stop rail against which said hammer rests; a striking pneumatic loosely connected with said hammer; 10 a stop limiting the impelling movement of said pneumatic; and a spring to return the hammer to its position of rest.

17. A harp stop for pipe organs having, in combination, vertically disposed glass sounding bars; an upstanding pivoted hammer for each of said bars, said hammer being weighted at its head and having a thickly padded striking face; a striking pneumatic loosely connected with said hammer; a stop 15 limiting the impelling movement of said 20

pneumatic; and a spring to return the hammer to its position of rest.

18. A harp stop for pipe organs having, in combination, vertically disposed glass sounding bars; an upstanding hammer for 30 each of said bars, said hammer being weighted at its head and having a thickly padded striking face; a striking pneumatic loosely connected with said hammer; and a stop limiting the impelling movement of 35 said pneumatic.

19. A harp stop for pipe organs having, in combination, glass sounding bars; a hammer for each of said bars, said hammer being weighted at its head and having a thickly padded soft striking face; and a striking pneumatic connected with said hammer. 40

In witness whereof, I have hereunto signed my name in the presence of two subscribing witnesses.
